UNITED STATES PATENT OFFICE.

MORRIS LEVITAN, OF NEW YORK, N. Y.

DESIGN FOR AN ELECTRIC-LIGHTING WALL FIXTURE.

Application filed August 12, 1926. Serial No. 18,700. Term of patent 3½ years.

To all whom it may concern:

Be it known that I, MORRIS LEVITAN, a citizen of the United States, residing at No. 868 Faile Street, borough of Bronx, city and State of New York, have invented a new, original, and ornamental design for Electric-Lighting Wall Fixtures, of which the following is a specification, reference being had to the accompanying drawing, forming a part thereof.

The figure shows a front elevational view

of my electric-lighting wall fixtures, the right arm and candle support being shown unornamented, it being understood, however, that the ornamentation of these features involves a mere repeat of that shown on the left side of the figure.

I claim:

The ornamental design for an electric-lighting wall fixture, as shown.

MORRIS LEVITAN.
